UNITED STATES PATENT OFFICE.

LOTHAR R. ZIFFERER, OF NEW YORK, N. Y.

ICE-PICK AND THE LIKE.

1,171,296.

Specification of Letters Patent.

Patented Feb. 8, 1916.

Application filed March 24, 1915. Serial No. 16,569.

To all whom it may concern:

Be it known that I, LOTHAR R. ZIFFERER, a citizen of the United States, residing at New York, in the county and State of New York, have invented certain new and useful Improvements in Ice-Picks and the like, of which the following is a specification.

My invention relates to a pick or similar instrument embodying in combination a handle and shank removable from each other to permit replacements when necessary. In instruments of this character it is quite common that the shank becomes broken or worn out, thus rendering the instrument incapable of further use. As the handle is not impaired by injury which affects the shank alone, it is uneconomical to discard the handle under such circumstances. In ice picks and similar instruments as usually constructed, however, the handle must be discarded whenever the shank becomes unfit for use. By a construction which enables the same handle to be used with successive shanks as replacements become necessary, the instrument may be available for use over a long period of time with no other expense than that required for shank renewals. Under the present invention such ends are attained in a simple and inexpensive manner.

In the drawing, Figure 1 is a longitudinal section through an ice pick embodying my invention; Fig. 2 is a transverse section taken on line 2—2 of Fig. 1, looking in the direction of the arrows; and Fig. 3 is a longitudinal section through a slightly modified form of ice pick.

I have shown in the drawing, a handle 4 made of a suitable material such as wood. Extending through the handle in a longitudinal direction is a central bore 5 of uniform diameter throughout. The handle is formed as is usual in such cases with a neck 6 from which portion the shank projects, a ferrule 7 being employed to surround the neck. Within the bore of the handle thus formed, I insert a sleeve 8, a portion 9 of which is enlarged to extend outside the handle body. An annular shoulder 10 is provided on the sleeve which bears squarely against the end portion of the neck of the handle covered by the ferrule 7. Preferably, this sleeve is secured within the handle by a drive fit, supplemented by a coating of lacquer or shell-lac at the time the sleeve is inserted within the body of the handle. This sleeve is

further secured within the handle by striking out points or projections 11, (see Fig. 2) from the end of the sleeve lying within the body of the handle. These points or projections can be conveniently formed by inserting from the head end of the handle, a tool equipped with tapered edges, and striking the same to cause the upper edge of the sleeve at the places of contact to be bent out to form the points 11, as shown. It is obvious that these projections will embed themselves within the material of which the handle is composed, in such manner as to prevent relative movement of any kind between the sleeve and handle.

The sleeve 8 is provided as shown, with a central bore to receive the shank 12 of a tool or instrument. At the inner end of the sleeve this bore is enlarged and threaded to provide a socket for receiving a set screw 13. The shank 12 is shown as provided with a head 14, capable of seating against the inner end of the threaded socket within the sleeve, thereby determining the position of the shank with respect to the handle. The set screw when threaded within the socket causes the shank to be positively held and secured within the handle.

It is manifest whenever the shank 12 becomes unfit for further use the set screw 13 can be unscrewed from the socket of the sleeve whereupon the shank 12 is capable of withdrawal through the handle. A new shank may then be substituted, the set screw reinserted, and the instrument rendered capable of further use, the same as when first assembled.

It is to be particularly noted that the enlarged head 9 of the sleeve extending outside of the handle body and against the overlying end of the ferrule 7, constitutes a positive abutment which receives and absorbs the shocks or impacts resulting from use of the instrument. By this construction, the handle is insured against likelihood of being split or otherwise worn, and loose movement or play between the handle and shank is eliminated. In Fig. 3, a very similar construction is shown. In this figure the bore extends within the handle from the neck through a distance just sufficient for the insertion of the sleeve 8, which in this case is exteriorly threaded. Manifestly the sleeve in this construction is secured within the handle by a threading action alone. The shank 12 and set screw 13, are initially as-

sembled within the sleeve before being inserted within the body of the handle, otherwise the construction is very similar to that shown in Fig. 1.

5. I claim:

1. A device of the class described embodying, in combination, a handle provided with a bore therewithin, said handle being formed with a neck of reduced diameter, a ferrule 10 surrounding said neck and overlying the handle and adjacent thereto, a hollow sleeve arranged within the bore of the handle provided at one end with an enlarged and threaded socket and at the other end with a head arranged to abut against the ferrule upon the handle neck, means for securing 15 said sleeve within the handle body, a shank within the sleeve having its acting end projected from the handle through the neck thereof, a head on the shank arranged to lie against the inner end of the threaded socket within the sleeve, and a threaded device 20 secured within said socket, and in engagement with the shank head to lock the same against movement, substantially as described.

2. A device of the class described embodying, in combination, a handle provided with a bore therewithin, a ferrule surrounding and overlying one end of the handle, a hollow 30 sleeve within the bore of the handle provided at one end with an enlarged and threaded socket and at the other end with a head arranged to abut against the ferrule end of the handle, means for securing said sleeve within the handle body consisting of a projection struck out from the sleeve into the handle body, a shank within the sleeve having its acting end projected from the handle through the ferrule end thereof, a head on 35 the shank arranged to lie against the inner end of the threaded socket within the sleeve, and a threaded device secured within said socket and in engagement with the shank head to lock the same against movement, 40 substantially as described.

45 3. A device of the class described, embody-

ing, in combination, a handle provided with a bore therewithin, a ferrule surrounding and overlying one end of the handle, a non-yielding sleeve arranged within the bore of 50 the handle provided at one end with an enlarged and threaded socket, means for securing said sleeve within the handle body, a shank within the sleeve having its acting end projected from the handle through the 55 ferrule end thereof, a head on the shank arranged to lie against the inner end of the threaded socket and in engagement with the shank head to lock the same against movement, substantially as described.

60 4. A device of the class described, embodying in combination a handle provided with a bore therewithin, a non-yielding sleeve within the bore of the handle, a shank within the sleeve having its acting end projected from the handle, a head on the shank normally disposed within the sleeve, said sleeve being provided with means for engaging 65 with the shank head to lock the shank against longitudinal movement in one direction, and other means independent of the sleeve for preventing longitudinal movement of the shank therewithin in an opposite direction, substantially as described.

70 5. A device of the class described, embodying in combination a handle provided with an axial bore therewithin, a sleeve within the bore of the handle, a shank within the sleeve having its acting end projected from the handle, said shank and sleeve 75 being configured to prevent longitudinal movement of the shank within the sleeve in one direction, and removable locking means axially aligned with the shank to prevent longitudinal movement of the shank in 80 the opposite direction, substantially as described.
